HOOD FASTENER

Filed July 7, 1930

UNITED STATES PATENT OFFICE

STEPHEN DE ORLOW, OF EAST LANSING, MICHIGAN, ASSIGNOR TO TERNSTEDT MANUFACTURING COMPANY, OF DETROIT, MICHIGAN, A CORPORATION OF MICHIGAN

HOOD FASTENER

Application filed July 7, 1930. Serial No. 465,936.

The present invention pertains to a novel fastener designed particularly for holding down the hood of a motor vehicle.

One of the objects of the invention is to provide a device of this character carried by the hood at the inner face thereof and movable therewith, as distinguished from present fasteners carried by the hood sill and disengageable from the hood to release the latter. The device of the present invention, being carried by the hood as stated, fastens to a detent carried by a fixed part of the vehicle, such as the back of the radiator, the front of the cowl structure or the sill.

A further object of the invention is to provide a fastener which may be made of stamped metal parts, excepting such small standard pieces as springs, screws and studs. According to the present invention, stampings are used for the pull rod or plunger, the bracket guiding the same, the locking piece and finger piece, and the detent engageable by the locking piece.

The invention is fully disclosed by way of example in the following description and in the accompanying drawing, in which—

Figure 1 is a longitudinal section of an automobile hood, showing the latch in locking position;

Fig. 2 is an elevation of the device, partly in section, directly adjacent the inner face of the hood;

Fig. 3 is a detail elevation of the pull rod;

Fig. 4 is a plan view of the member constituting the latch and finger piece;

Fig. 5 is a plan view of the detent; and

Fig. 6 is a vertical section of a modified construction, showing the same in release position.

Reference to these views will now be made by use of like characters which are employed to designate corresponding parts throughout.

The conventional form of automobile hood is designated by the numeral 1 in Figure 1 where it is shown in section. To the inner side of the hood is suitably fastened a bracket 2 having upper and lower lugs or ears 3 and 4 respectively. A pull rod or support 5 is

passed slidably through the ears in substantially parallel relation to the side of the hood 1 and is formed at its lower end with an upwardly and inwardly extending foot 6. A lug 7 projects laterally from the heel of the foot 6 for a purpose which will presently appear.

To a suitable fixed part of the automotive vehicle, such as the back of the radiator or the forward side of the cowl structure, is secured a detent or keeper consisting, for example, of a back plate 8 attached to such fixed portion by screws 9 and having a flange 10 extending therefrom and preferably curled at 11 at the operative end for reinforcement. It will be evident that the detent member, as well as the bracket 2 and rod 5 may be made from sheet metal by stamping operations.

The pull rod is supported in the bracket by a spring structure presently to be described, and this spring structure draws a locking member against the detent as will also presently appear.

The locking member is also in the nature of a stamping and includes moreover the finger piece for operating the device. This member may be described as having a shank 12 of double thickness metal received in a slot 13 in the hood 1 and formed at one end with a finger loop 14 on the outer side of the hood. The hook or locking portion 15 of this member is also constructed of double metal shaped to straddle the foot 6 over the upper edge thereof as may be seen by reference to Figures 1, 2 and 4. This portion 15 extends upwardly and inwardly, parallel to the foot 6, when the shank 12 is in horizontal position as shown in Figure 1. In this position, the locking portion 15 rests upon the lug 7 which extends from the foot 6.

The locking portion 15 is adapted to engage beneath the curl or bead 11 and is drawn against the latter member by a spring 16 surrounding the pull rod 5 between the ears 3 and 4. The lower end of the spring bears upon the lower ear 4, while the upper end bears against the disk 17 surrounding the rod and limited in its upward movement by a pin 18 passed through the rod. It is also to be noted that the toe of the foot 6 is aper-

tured at 19 for permanent pivotal connection to the inner end of the locking portion 15 by means of a pivot pin 20.

In Figure 6 is illustrated a modified construction differing only in the detent. This modification is designed for instance where it is desired to mount the detent on the sill rather than on vertical parts. Accordingly, there is provided a stamping 21 standing principally in a vertical plane and adapted to be fastened to the sill by means of a stud 22. A slot 23 is formed in the stamping by striking out a piece of metal and leaving the same integral with the blank at the upper edge of the slot thus formed. The metal which is thus struck out is rolled to form a bead or curl 24 at the upper edge of the slot, adapted for engagement by the locking portion 15 in the same manner as the bead 11 in Figure 1. The locking portion 15 and the foot 6 of the pull rod 5 are obviously adapted to pass through the slot 23, and the remaining parts of the structure are shaped and assembled as described in connection with Figures 1 to 5.

In the use of the device it will be seen by reference to Figure 1 that the spring 16, acting on the locking portion 15 through the lug 7, normally draws the portion 15 against the bead on the detent. In order to release the hood from the detent, the finger piece 14 is swung upwardly on its pivot 20 until the shank 12 engages the upper edge of the slot 13. Further tilting of the finger piece 14 and locking member around the upper edge of the slot 13 as a fulcrum draws the foot 6 away from the bead of the detent, against the action of the spring 16, as illustrated in Figure 6. The upper edge of the locking member 15 has now assumed a downward and inward slope, whereupon it may readily be released from the detent to permit lifting of the hood by an upward pull on the finger pieces 14.

Although a specific embodiment of the invention has been illustrated and described, it will be understood that various alterations in the details of construction may be made without departing from the scope of the invention as indicated by the appended claims.

What I claim is:

1. In a latch for the hoods of automotive vehicles, a keeper secured inside the hood to a stationary part of the vehicle, means mounted on the inside of the hood for slidable movement only, a foot on said means capable of being pushed under the keeper when the hood is latched, said foot having no contact with said keeper, a hook pivoted to said foot, said hook having a handle extending outside the hood and operating said hook to cause it to become engaged with or disengaged from the keeper.

2. In a latch for the hoods of automotive vehicles, a keeper secured inside the hood

to a stationary part of the vehicle, a bracket rigidly secured inside the hood adjacent said member, means mounted in the bracket for slidable movement only and extending under said member, said means having no contact with said keeper, a hook pivoted to said means and capable of extending under the keeper, said hook having a handle extending outside the hood and capable of being moved to cause said hook to become engaged with or disengaged from the keeper.

3. In a catch for the hoods of automotive vehicles, a keeper inside the hood mounted on a stationary part of the vehicle, a movable member secured to the hood, a hook pivoted to the movable member, a part of both of said member and hook adapted to extend under the keeper, said member being at all times out of contact with said keeper, and a handle for moving said hook to cause it to become engaged with or disengaged from the keeper.

4. In a catch for the hoods of automotive vehicles, a keeper secured to a stationary part of the vehicle, means mounted inside the hood for slidable movement only, a foot on said means extending under said keeper but out of contact therewith when the hood is latched, a hook attached to said foot and adapted to extend under the keeper to engage the same to hold the hood in latched position, said hook having a handle extending outside the hood, the operation of said handle tripping both said hook and foot from the keeper to release the hood.

5. In a catch for the hoods of automotive vehicles, a keeper secured to a stationary part of the vehicle, means mounted inside the hood for slidable movement only, a foot on said means extending under said keeper when the hood is latched, a hook attached to said foot, said hook having a handle extending outside the hood, the operation of said handle tripping both said hook and foot from the keeper to release the hood, said hook only contacting with said keeper when the catch is in latched position.

6. In latching means for the multiple hinge closure of an automobile hood, a keeper positioned within the hood, a latch bolt positioned within the closure and means, mounted on the closure, for guiding it for movement along a generally upright path, yielding means tending normally to move it upwardly along said path, and a lever mounted on said latch bolt, for rotation about an axis lying, when the latch is in latching position, at a point more remote from the inner face of the closure than is the keeper, said lever including a unitary exterior handle portion extending outwardly through an aperture in the closure, and a portion adapted, when the handle is at one limit of its arc of rotation, to maintain a locking connection with the keeper, and

adapted, when the handle lever is at the opposite limit of its rotation, for ready withdrawal from the keeper.

7. In latching means for the multiple hinge closure of an automobile hood, a keeper positioned within the hood, a latch bolt positioned within the closure and means, mounted on the closure, for guiding it for movement along a generally upright path, 10 yielding means tending normally to move it upwardly along said path, and a lever mounted on said latch bolt, said lever including a unitary exterior handle portion extending outwardly through an aperture in the closure, and a portion adapted, when the handle is at one limit of its arc of rotation, to maintain a camming locking connection with the keeper, and adapted, when the handle lever is at the opposite limit of its rotation, 15 for ready withdrawal from the keeper.

8. In latching means for the multiple hinge closure of an automobile hood, a keeper positioned within the hood, a latch bolt positioned within the closure and means, 20 mounted on the closure, for guiding it for movement along a generally upright path, yielding means tending normally to move it upwardly along said path, and a lever mounted on said latch bolt, said lever including a 25 unitary exterior handle portion extending outwardly through an aperture in the closure, said lever being provided with a locking portion adapted to penetrate to the rear of the keeper when the handle is at one limit 30 of its arc of rotation, to maintain a locking connection with the keeper, said locking portion lying, when the handle lever is at the opposite limit of its arc of rotation, substantially in the horizontal plane of the lowest 35 portion of the keeper.

9. In latching means for the multiple hinge closure of an automobile hood, a keeper positioned within the hood, a latch bolt positioned within the closure and means, 40 mounted on the closure, for guiding it for movement along a generally upright path, yielding means tending normally to move it upwardly along said path, and a lever mounted on said latch bolt, said lever including 45 a unitary exterior handle portion extending outwardly through an aperture in the closure, and a portion adapted, when the handle is at one limit of its arc of rotation, to maintain a locking connection with the keeper, 50 said portion being withdrawn from locking relationship with the keeper in response to 55 unlatching movement of the handle.

10. In latching means for the multiple hinge closure of an automobile hood, a keeper 60 positioned within the hood, a latch bolt positioned within the closure and means, mounted on the closure, for guiding it for movement along a generally upright path, yielding means tending normally to move it upwardly along said path, said latch bolt in- 65

cluding a hook portion adjacent the lower end thereof, and a lever mounted on said latch for rotation about an axis positioned in said hook portion, and means for rotating said lever from without the closure, including an exterior handle unitary with said lever.

In testimony whereof I affix my signature.

STEPHEN DE ORLOW.
